UNITED STATES PATENT OFFICE.

JOSEPH PRICE, OF NEW YORK, N. Y., ASSIGNOR TO THE GRISCOM RUSSELL COMPANY, OF NEW YORK, N. Y., A CORPORATION OF DELAWARE.

METHOD OF MAKING SPIRAL COILS.

Application filed May 7, 1921. Serial No. 467,658.

To all whom it may concern:

Be it known that I, JOSEPH PRICE, a citizen of the United States, residing at No. 203 West 11th Street, in the city and county of New York, State of New York, have invented certain new and useful Improvements in Methods of Making Spiral Coils; and I do hereby declare the following to be a full, clear, and exact description of the invention, such as will enable others skilled in the art to which it appertains to make and use the same.

The present invention relates to method and apparatus for forming spiral coils adapted to be used in apparatus for exchanging heat between fluids, particularly of coils of the general type disclosed in my co-pending application, Serial No. 275,746, filed February 8, 1919.

Heretofore coils of this type have been formed by winding a length of straight tubing into the desired spiral form, beginning at the center of the coil where the radius of the turns is small and winding on successive turns until a coil of the desired diameter is produced. In forming double coils the winding must be begun approximately at the middle of the tubing. The portion from the middle to one end of the tubing is wound into one flat spiral coil and the other half of the tubing into another flat coil in parallelism with the first, a sufficient length of tubing being left at the middle to constitute a continuous fluid passage from one of the flat coil elements to the other. Since successive turns of the spiral enclose preceding turns, it is impossible to accomplish the winding of such a coil upon a spool or other type of form block, and the winding has heretofore been accomplished by hand.

It is the principal object of the present invention to provide a method for forming flat spiral coils of the above type which may be carried out conveniently and quickly and at low expense and in which few hand operations are necessary.

It is also an object of the invention to provide a method for forming spiral coils which may be employed equally well in the manufacture of double coil units in which the two elements are identical, those in which the two elements are reversely wound, as well as those in which the corresponding turns of the two elements con-

stituting the coil unit are staggered relative to the axis of the coil, which two latter constructions possess certain peculiar advantages which will be later described.

In the accompanying drawings I have illustrated the manner of forming flat spiral coils according to my improved method and have illustrated a preferred embodiment of apparatus therefor.

In said drawings,

Figure 1 is a plan view showing the mandrel of the machine and its operating mechanism;

Fig. 2 is a vertical section through the center line of the mandrel;

Fig. 3 is an end view looking from the right of Figs. 1 and 2 and showing also the tube-support and guide;

Figs. 4 and 5 are diagrammatic views showing the movement of the tube guide during the coiling of the tube;

Fig. 6 is a detail view of a portion of the tube guide;

Fig. 7 is an elevational view showing the coiled tube immediately after it is removed from the mandrel;

Figs. 8 and 9 show in section and elevation, respectively, the completed coil;

Fig. 10 is an elevational view of the modified form of mandrel for producing a different type of coil;

Fig. 11 is an elevational view showing the tube ready for coiling on the mandrel shown in Fig. 10;

Fig. 12 is an elevational view showing the modified coil as removed from the mandrel; and

Figs. 13 and 14 show in section and elevation, respectively, the completed coil produced on the mandrel shown in Fig. 10.

Referring to Figs. 1 to 3 of the drawings, 1 indicates my improved mandrel which comprises two independent portions 2 and 3 having the form of cone frustums with their smaller ends adjacent, thus lending the assembled mandrel a form similar to that of an hour-glass. The cooperating portions 2 and 3 of the mandrel are attached to a common shaft 5. This shaft is of sufficient length to extend through the split bearing 6, which is carried by a pedestal or frame member 7 and which serves to support the shaft and mandrel for rotation. The overhanging portion of the shaft is provided with a worm gear 9 fixed to the shaft and serving

to rotate the mandrel from a suitable power source, for instance, the individual electric motor 10 and clutch 11 shown in the drawings.

The opposite end of the shaft 5 extends 5 through the hub of the mandrel portion 2 and terminates in a threaded portion 13. A portion of the shaft 5 adjacent its bearing is squared, as shown, and a part 2 of the mandrel is supported on the squared portion of 10 the shaft so as to slide freely thereon. The outer part 3 is detachably secured to the shaft so that it may be readily removed. For this purpose there is provided a hand wheel 14 having an attached threaded collar 15 adapted to engage with the threads 13 provided on the end of the shaft 5. At the inner end of the threaded portion 15 is a 15 flange 16 of diameter substantially equal to the outer diameter of the hub of the mandrel portion. By screwing up the hand wheel 14 the mandrel portion 3 is firmly clamped between the fixed inner portion and the flange 16 of the hand wheel. A plate 17 which is diametrically split for the purpose of assembly may be fitted over the portion 15 and secured to the mandrel portion 3 by means of screws 18. This plate is adapted to engage against the outer face of flange 16 so that the mandrel portion will be positively drawn 20 away from the fixed mandrel portion by unscrewing the hand wheel.

The outer mandrel portion 3 has a square counter-bore in its small end to fit over the end of the squared portion of the shaft which 25 projects somewhat beyond the small end of the mandrel part 2, thus assuring that the two parts of the mandrel will be fitted properly together and will be held against relative movement while the machine is in operation. The faces of the mandrel portions 2 and 3 are provided with a groove 19 of form depending upon the particular type of coil which it is desired to produce. For producing spiral coils the groove begins near the 30 upper edge of the mandrel portion 2 and proceeds in a spiral course down the mandrel, the radius of its turns decreasing as it approaches the center of the mandrel, and assumes essentially the shape of a conical 35 spiral. The face of the mandrel portion 3 is an exact complement of the portion 2, and when placed end to end with the portion 2 a groove is formed extending continuously along the mandrel from end to end. If desired, a spiral track or series of brackets 40 arranged in spiral form may be positioned upon the surface of the mandrel for the purpose of shaping the tubing into the desired form instead of employing a groove 45 as shown.

A clamping plate 20 is provided at the outer edge of the mandrel portion 2 for holding in place the end of the tubing which is being formed into a coil. The plate is secured in place by means of a bolt 21 and nut 50

22. There is also provided at the outer edge of the mandrel portion 3 a handle 23 rigidly attached to the mandrel by means of a screw 24. This handle is designed as a convenient means by which to properly position the mandrel before the tubing is secured in place, and to furnish means by which the outer mandrel portion may be unscrewed from the coiled tube for dislodging the tubing from the groove 19 after the coil has been wound, so that the mandrel portion 2 may be withdrawn. The free end of the mandrel may, if desired, be supported in a fixed ring 40 provided with bearing rollers 41, to relieve the bearing 6 of the overhung load tending to depress the mandrel during the coiling of the tube.

For the purpose of properly forming the coil tubing 1 on the mandrel, an independent vertical supporting stand 25 carrying a ball joint 26 is provided opposite the middle section of the mandrel and at some distance therefrom. Plunger rod 27 is screwed at one end into the ball joint 26 and extends from this joint to the mandrel. Rod 27 serves as a supporting core for the length of tubing 1 which is being formed into a coil, the tubing being first slipped over the supporting rod and then drawn off by the rotation of the mandrel.

The ball joint 26 is mounted for pivotal movement in a vertical direction and is also free to rotate about its vertical axis, thus giving the working end of the plunger rod 27 freedom to move from end to end of the mandrel and also to follow the pitch of the mandrel as the diameter of the turns varies. The ball joint is preferably placed at a level somewhat above that of the mandrel axis for the purpose of causing the end of the plunger rod in following the surface of the mandrel to lie more nearly in the vertical plane passing through the axis of the mandrel than would be the case if the ball joint were supported at the same height as the mandrel shaft, in which case the end of plunger rod 27 would describe roughly an arc each time it traveled from one end of the mandrel to the other. A longitudinal passage is provided throughout the length of the plunger rod and serves to deliver a cooling and lubricating fluid to the tubing being formed. This fluid may be introduced through a tubing 28 attached to the threaded end of the plunger rod, and after traversing the length of the plunger rod and that portion of the coil already wound on the mandrel it escapes on the open end of the coil tubing.

In forming a coil the mandrel is turned 125 manually to the desired position by means of handle 23. A straight length of tubing is then selected and slipped over the plunger rod 27. The end of the tubing adjacent the mandrel is inserted beneath the clamp-

ing plate 20 and the nut 22 tightened to secure it firmly in place. The power source is then connected to the apparatus and the mandrel rotated at a predetermined speed, 5 the length of tubing being drawn off the plunger rod and wound upon the mandrel as the rotation proceeds. The grooved track on the mandrel face serves as a guide for the tubing being wound, and since the 10 plunger rod is free to move about in all directions, the tubing will wind up on the mandrel until the desired length of tube has been wound on the mandrel. The plunger rod may then be moved away from 15 the mandrel in a longitudinal direction by screwing it back through the ball joint, for the purpose of removing its end from the coil, which is usually left as shown in Fig. 9 to provide sufficient end for attachment 20 to the apparatus in which it is to be used.

The chief purpose of the plunger rod is to prevent the tube collapsing at the point where it begins to bend and for that reason it is essential that the end of the rod 25 move as closely as possible in the vertical plane of the axis of the mandrel, which is accomplished, as described above, by supporting the outer end of the rod at the proper distance above the axis of the mandrel. The relation of the rod to the mandrel is graphically illustrated in Figs. 4 and 5. As shown in Fig. 4, the length of 30 the rod is such that when pivoted in line with the middle of the mandrel, that is on line $a-a'$, the end of the rod due to its movement in a horizontal plane as indicated by arc $a'-a'$ will intersect the plane of the axis of the mandrel at the large ends of the mandrel. As shown in Fig. 5, the 35 height of the ball joint is so determined that the vertical movement of the end of the mandrel as indicated by arc $b'-b'$ causes the end of the mandrel to lie in the vertical plane of the axis of the mandrel at the 40 point of its smallest diameter. As the movement of the end of the rod is both vertical and horizontal in following the surface of the mandrel its end face lies substantially at all times in the plane of the mandrel 45 axis.

The mandrel is kept in rotation until the entire groove from the upper end of the mandrel portion 2 to the upper end of the mandrel portion 3, or any desired portion 50 thereof, is filled, at which time the power is shut off and the apparatus brought to rest. The hand wheel 14 is then turned to unclamp the mandrel sections and by means 55 of the plate 17 and flange 16 to shift the mandrel section 3 off the squared portion of the shaft 5. In this movement the part 2 will also be moved along the shaft by the tube which is wound around both mandrel parts, until the part 3 is entirely off 60 the squared portion of the shaft 5. The

hand wheel 14 will preferably be screwed completely off the end of the shaft so that the mandrel part 3 may be turned manually about the reduced round portion of the shaft 5 by means of handle 23 in a direction opposite to that in which groove 19 converges toward the center of the mandrel to thereby unscrew the mandrel section 3 from the coil tubing. When unscrewed sufficiently for the tubing to be 70 clear of the spiral groove, the mandrel portion 3 may be completely removed. The clamping plate 20 will then be unfastened to release the end of the tube and thus permit the coil tubing to be unscrewed and removed from the mandrel section 2. The mandrel is now reassembled by returning the portion 2 in place on its shaft 5 in proper relation with the part 3 and screwing up the hand wheel 14, after which another 75 coil may be formed.

The character of the coiled tubing as it comes from the mandrel is illustrated in Fig. 7. The free ends 30 and 31 are at the outer extremities of the conical portions 80 and occur on the turns of largest diameter. To form a double flat spiral coil, each of the conical portions of the coil as it comes from the mandrel is pressed into a flat coil by any convenient means, thus forming two closely 85 adjacent parallel flat coils 35 and 36 as shown in Fig. 8 and Fig. 9. Since the grooves on the two mandrel portions were so positioned as to cause the turns of one portion to be directly opposite the spaces between 90 turns on the other portion, the turns of the flat coils produced after the pressing operation lie in staggered relation to the direction of the axis of the coil. This feature is of value in apparatus for exchanging heat 95 between fluids due to the fact that it causes the fluid to be filmed through the spaces formed between the staggered coil turns and insures good contact with the heat transferring surface. The coil ends 30 and 31 100 are here shown extending out in parallelism at one side of the coil but may be made to assume other positions by cutting off one of the coil ends at a different length so that its opening will occur at a different 105 point on the periphery of the coil.

While the staggered relation of turns prevails throughout the greater portion of the coil it will be observed from Fig. 9 that at two diametrically opposite points 33 the 110 adjacent turns of the two flat coil portions cross each other, and at these points a free passage will occur through the double coil unit in the direction of the coil axis. Should successive coil units be positioned 115 in a heat transferring apparatus in identical relation throughout the length of the apparatus these open spaces would all fall in line, and there would be a tendency for some of the fluid passing through the ap- 120

paratus to flow down through these available openings without being sufficiently filmed into intimate contact with the various coil turns. If, however, successive coil units 5 are positioned in the apparatus so as to be angularly displaced somewhat about their transverse axis these open spaces will not fall in line but will be staggered from one coil to the next. The coil units may be 10 adapted for such displacement by causing the inlet and outlet openings 30 and 31 to be positioned at different portions of the periphery in different coil units. For example, the end 30 may be shortened some- 15 what and the end 31 may be lengthened an amount equal to that by which the end 30 is shortened, thus leaving the inlet and outlet openings in the same position relative to each other but displaced a certain 20 angular distance relative to the body of the coil.

This difference in the coils may readily be secured with the machine herein disclosed by merely changing the position 25 of the clamping member 20. For the purpose the flange of the mandrel is provided with a series of holes in any one of which the bolt 21 may be set to give the clamping member 20 a range of angular movement 30 about the shaft 5 of about 90°, or any other desired amount. For the purpose of permitting the tube ends of the completed unit the same relation to each other, the winding of the tubing is continued farther 35 on the mandrel portion 3, this operation being accomplished with no appreciable change in the finished coil. In a given heat exchange apparatus one half of the coils may be of the type formed with the clamping member 20 in its normal position and the other half of the type formed with the clamping member 20 displaced 90°. When the coils are placed in the apparatus, alternate coils being of the different types, a 40 staggered relation will be secured and a free fluid passage through the length of the shell will be eliminated.

In Fig. 10 I have illustrated a mandrel adapted to form double flat spiral coil units 50 in such manner as to avoid having a free passage for the fluid through both coils of the unit at any portion of the coil. The mandrel is divided into two portions 2^a and 3^a which may be mounted for rotation in 55 the manner already described. Each of the portions 2^a and 3^a has a spiral groove provided at its face, the direction of the groove upon the portion 3^a being the reverse of that on the portion 2^a. In the 60 apparatus shown in Fig. 2 a continuous rotation in a clockwise direction will cause the tube to follow the groove on to the end, while in the mandrel shown in Fig. 10 the 65 groove begins at the large end of section 2^a and proceeds down to the center of the

mandrel 1 in a clockwise direction, but the mandrel portion 3^a is grooved oppositely to the portion 2^a and proceeds outwardly from the center in a counterclockwise direction. The grooves of the mandrel portion 70 2^a are positioned relative to those on the portion 3^a so that they lie opposite the spaces between grooves on the portion 3^a.

In forming a coil by means of this type of mandrel the length of tubing is first bent 75 at its middle to conform with the loop 34 formed by the meeting grooves in the two parts of the mandrel. The bent middle portion 34^a of the tube is placed at the center of the mandrel where it is clamped in fixed position by means of a bolt with a wide head which is screwed into the mandrel part 3^a at the beginning of its groove. Upon rotating the mandrel the two halves of the tubing wind up simultaneously in the 80 grooves on the mandrel portions 2^a and 3^a, forming two conical spiral coils reversely wound and connected by the middle bent portion. The two spiral portions of the 85 coil are subsequently pressed flat and a flat double coil unit is formed, the turns of the elements constituting each coil being staggered relative to the axis of the coil.

It is to be noted that the turns of the two 90 flat coil elements comprising each unit lie 95 in exact parallelism, the turns of one being exactly opposite the spaces between turns of the other at all portions of the unit, thus avoiding altogether points on the coil at 100 which the spaces between turns of one come directly opposite the spaces between turns of the other. This modification thus furnishes a completely staggered path for the 105 fluid through the unit.

In the type of construction illustrated in 110 Figs. 7 and 9 the working fluid passes completely through the coil unit from the inlet positioned at the periphery of one of the flat coil elements to the outlet positioned on the periphery of the other flat coil element, the direction of flow being the same throughout the coil. Thus the turns of one coil proceed from the outer edge of the unit to 115 the inside, decreasing in radius, and the turns of the other element increase in radius and proceed from the inner to the outer portion of the coil, which feature necessitates a crossing of the turns of the two flat coil elements and the forming of points at which the staggered relation is not maintained. 120 In the reversely wound coil, however, the fluid passes from the inlet at the outer portion of one of the flat coil elements to the inner turns, but at the center the flow is reversed and the fluid passes from the inner 125 turns of the second flat coil element to the outlet at the periphery of the element in the reverse direction.

While I have illustrated and described a 130 preferred manner of carrying out my im-

proved method of forming heat exchanging coils of the type described and have illustrated a preferred embodiment of apparatus therefor, it is to be understood that the de-

tails of the method and particular construction of the apparatus may be varied within the full scope of the appended claims. For instance, the end of the mandrel farthest from the bearing 6 may be supported by another bearing, instead of being mounted to rest upon rollers in the manner shown. If the mandrel is of unusual length a traveling carriage mounted for movement parallel to the mandrel axis may be employed in feeding the tubing instead of the ball joint arrangement as shown. Also any desired arrangement of clutch mechanism may be provided to effect rotation of the mandrel.

I claim:

1. The method of forming flat spiral coils for heat exchanging apparatus comprising winding the material of the coil into a conical spiral and subsequently compressing the turns of said spiral into substantially the same plane.

2. The method of forming double flat spiral coil units for heat interchange apparatus comprising winding the material of the coil into two conical spirals and subsequently pressing the turns of each conical spiral into substantially a single plane.

3. The method of forming double flat spiral coil units for a heat exchange apparatus comprising winding the material of the coil into two conical spirals having their small ends adjacent, the material of the coil being continuous throughout the length of both spirals, and subsequently compressing the turns of each spiral into substantially a single plane.

4. The method of forming double flat spiral coil units for heat exchange apparatus, comprising winding a straight tubing into two co-axial conical spirals and subsequently compressing the turns of each spiral into

substantially a single plane, the tubing forming a continuous fluid passage through said spirals in series.

5. The method of forming double flat spiral coil units for heat exchange apparatus, comprising forming the material of the coil into two reversely wound conical spirals having their smaller ends adjacent, the turns of one of said spirals being opposite the spaces between turns of the other.

6. The method of forming double flat spiral coil units for heat exchange apparatus, comprising winding the material of the coil into two conical spirals and subsequently compressing the turns of each spiral into substantially a flat coil, said flat coils lying closely adjacent and the turns of each of said coils being directly opposite the interstices between turns of the other.

7. The method of forming double flat spiral coil units for heat exchange apparatus, comprising winding up a length of tubing into a conical spiral form, then reversing the direction of the tubing, then winding up another conical spiral in a direction reversed from that of said first spiral and subsequently flattening the respective conical coils into a double flat spiral coil.

8. The method of forming double flat spiral coil units for heat exchange apparatus, comprising winding up a length of straight tubing into a coil of a conical spiral conformation beginning at the larger end and working toward the apex of the cone, then reversing the direction of the tube at the apex and winding up a second coil of conical spiral conformation beginning at the apex and proceeding toward the base, the turns of said second coil lying opposite the interstices between turns of said first coil, and then suitably flattening said respective coils to form a double flat spiral coil unit.

In testimony whereof I affix my signature.

JOSEPH PRICE.
